MINE CAR SEALING DEVICE

Robert E. Jones, Knoxville, Tenn., assignor to
The Sanford Investment Company, Wilming-
ton, Del., a corporation of Delaware

Application April 8, 1949, Serial No. 86,331

6 Claims. (Cl. 105—253)

1

This invention relates to improvements in mine car sealing devices, particularly for sealing the drop bottom doors of mine cars used for transporting coal or other materials from a loading point to a point of discharge, where such materials are discharged through the bottom of the car upon release of the drop bottom doors therein.

In mine cars used for the transportation of coal and other loose lading, it is important that the drop bottom doors be sealed at the opposite edges thereof against the leakage of coal between the edges of the doors and the side sills of the car. It is difficult to form the doors so these will fit so closely to the inside faces of the side sills as to prevent the leakage of loose coal therebetween. Consequently, special provision should be made for sealing the space between the edges of the doors and the side sills against the leakage of coal therebetween.

In mine cars of the character in which the wheels are deeply recessed into the side walls, leakage occurs also between the wheel hoods that cover the wheels and the adjacent portions of the doors, especially where drop bottom doors are hinged between the hoods. Provisions have been suggested heretofore for sealing the edges of the doors between the hoods, but these have required rather special fabrication, in order to provide the necessary sealing action.

An object of this invention is to improve the construction of mine cars and the other vehicles, especially of large capacity, and particularly the means for sealing the lateral edges of the bottom doors between the wheel hoods, without increasing materially the cost of fabrication of the vehicles nor adding to the complexity thereof.

A further object of the invention is to improve the construction of the tie connection between the wheel hoods, whereby the transverse tie plate extending therebetween which joins opposed hoods may be utilized also for sealing the edges of the doors at the inner sides of the wheel hoods without requiring additional fabrication of special sealing means therefor.

This object may be accomplished, according to certain embodiments of the invention, by the provision of a tie plate which extends transversely between opposed hoods over the wheels and is joined thereto at the inner faces of the hoods, with wings or extensions on the lateral edges of the tie plate overlapping the crack between the lateral edges of the doors and the inner faces of the hoods. These wings or ex-

2

tensions may be formed so as to extend throughout the length of the tie plate or to be provided only at the opposite ends thereof, whichever may be desired, but project inwardly from the inner faces of the wheel hoods sufficiently to overlap the adjacent edges of the doors and thereby seal the checks between the lateral edges of the doors and the inner faces of the wheel hoods. This saves materially in the cost of fabricating the car as compared with special provisions for sealing these portions of the doors which otherwise would add considerably to the cost of constructing the car both in labor and material.

Certain embodiments of the invention are illustrated in the accompanying drawings in which:

Fig. 1 is a side elevation of an end portion of a mine car showing the invention applied thereto;

20 Fig. 2 is an end elevation thereof;

Fig. 3 is a longitudinal sectional view through a side of the car at the wheel hood and tie plate thereof, substantially on the line 3—3 in Fig. 4;

Fig. 4 is a cross section therethrough on the line 4—4 in Fig. 3;

Fig. 5 is a detail section on the line 5—5 in Fig. 4;

Fig. 6 is a top plan view thereof;

Fig. 7 is a longitudinal sectional view through a modified form of tie plate;

Fig. 8 is a top plan view thereof; and

Fig. 9 is a cross section of the tie plate as applied to a modified form of door structure.

While the invention may be applied to various forms and types of vehicles, such as mine cars, trucks, wagons, etc., it is shown merely for purpose of illustration of one embodiment of the invention as used in connection with a 4-wheel mine car of the character having drop bottom doors adapted to be latched in closed position and to be released for dumping the lading between the tracks.

In this form, as illustrated particularly in Figs. 1 to 5, the wheels are designated generally by the numeral 1, mounted on axles 2, which axles are connected with side sills 3, by hanger bushings 4 (Figs. 3 and 4). The side sills 3 extend lengthwise of the car and are connected at their opposite ends with combined end sills and bumpers generally designated at 5, cooperating therewith to form the frame structure of the car.

Supported upon the side sills 3 are side walls generally designated at 6, that extend upwardly and outwardly from the upper edges of the re-

spective side sills, and joined to end walls 7, at the respective opposite ends of the car. As shown in Figs. 2 and 3, the wheels 1 are deeply recessed in the respective side walls 6, and are covered by wheel hoods 8, extending thereover. The wheel hoods 8 are provided with end walls 9, closing the inner ends thereof and secured to the side sills 3.

The car is of the type having a plurality of drop bottom doors generally designated at 10, each of which is shown as pivotally supported on a hinge rod 11, as illustrated in Figs. 1 to 5, which hinge rods are mounted in brackets 12, secured to the inner faces of the opposed side sills 3. In this form of the invention, the doors are shown as of the overlapping type, wherein the free edge of one door 10, is supported upon the hinge edge of the next rearward door in such relation that swinging movement of said rearward door will remove the hinge edge thereof out of supporting relation with the free edge of the next forward door so as to release the doors for dropping. In this form of the invention, the rearward door has the free edge thereof latched capable of being released for opening the doors to dump the lading.

Each of the doors 10 extends from side to side of the car, substantially to close the space between the inner faces of the side sills 3, although clearance is provided therebetween as indicated at 13 in Fig. 3, to permit freedom of swinging movement of the doors with respect to the side sills. The free edges of the doors may be provided with upturned flanges or edge bars 14, extending along the length thereof.

The axles 2 are covered by tie plates 15, that extend transversely of the car from side to side thereof between the inner walls 9 of the wheel hoods 8. The opposite ends of the tie plates 15 are adapted to be secured rigidly to the inner walls 9 of the wheel hoods in any suitable manner, by welding, riveting, etc. Angle bars 16 are shown as welded to the sides of the tie plates 15 at the ends thereof and to the inner face of the wheel hood wall 9, as a means of securing the tie plate thereto.

In the form illustrated in Figs. 1 to 5, the tie plate 15 is in the form of a plate bent to inverted V-form and disposed with its apex substantially in a plane through the axis of the axle 2, as will be evident in Fig. 4. Each of the opposite sides of the plate 15 is formed with extended wing sections 17, forming continuations thereof and of sufficient extent to project throughout the width of the wheel hood inner wall 9, overlapping the crack 13, between the opposite edges of the door and the inner face of the wheel hood wall. These wing sections 17 may extend directly in alignment with the respective sides of the tie plate 15 or be turned at an angle thereto, according to the desired form thereof, but are joined directly to the inner face of each wall 9, and thus seal the interior of the car against leakage through the cracks between the edges of the doors and said inner walls 9.

Thus provision is made for effectively sealing the doors against the leakage of coal or other lading at the inner ends of the wheel hoods. Any suitable means may be provided intermediate the wheel hoods for sealing the edges of the doors, one form of which is illustrated generally in Fig. 3, wherein the inner edges of the side walls 6, overlap the flange bars 14 of the doors, as indicated at 18, to cover the crack therebetween.

In the form illustrated in Figs. 1 to 5, the tie plates 15 extend in straight lines from side to side of the car, including the wing sections 17 thereon. If desired, however, these wing sections may be provided only at the opposite edges of the doors as illustrated in Figs. 7 and 8, while the intermediate portion of the tie plate 15, is cut away to its normal width as indicated generally at 15' in Figs. 7 and 8, while the wing sections are shown at 17' formed thereon, or connected therewith, at the opposite ends of the tie plate 15. These wing sections 17' extend substantially throughout the width of the wheel hood as described above and inwardly in overlapping relation with the crack between the door and the wheel hood wall, as will be evident from Fig. 7.

In Fig. 9 is illustrated a further modification in which the tie plate 15 of the same construction described above in Figs. 1 to 5 extends between the wheel hoods, but is provided with a flange 19 on one edge thereof, extending downwardly in overlapping relation with a portion of the door supporting means. In this form, the doors 10' are hinged at 11' adapted for longitudinal sliding movement into and out of supporting position in a manner well understood in the art, this being a construction utilizing doors that drop in 1-2-3 order, as described more in detail in Sanford Patent, No. 2,001,471. Otherwise the tie plate construction is similar to that described above in its construction and function.

This provision for sealing the cracks between the edges of the doors and the wheel hoods cooperates with the sealing means 18, intermediate the hoods, to provide continuous sealing throughout the length of the car.

While the invention has been illustrated and described in several embodiments, it is recognized that other variations and changes may be made therein without departing from the invention, except as specified in the claims.

I claim:

1. In a vehicle having a lading body with side sill structures separated and having a bottom opening therebetween for the discharge of lading therethrough, wheels for supporting the lading body, deeply recessed wheel hood coverings connected with the lading body on opposite sides thereof over the wheels, and a door for closing said bottom and having the edge portions thereof in relatively close proximity to the side sill structures, the combination of a tie plate extending between the opposite wheel hood coverings and connected therewith and having wing sections on opposite edges thereof extending in overlapping relation with the cracks between the door and the hood coverings substantially throughout the width of the latter.

2. In a vehicle having a lading body with side sill structures separated and having a bottom opening therebetween for the discharge of lading therethrough, wheels and axles for supporting the lading body, wheel hood coverings connected with the lading body on opposite sides thereof over the wheels and with the axles extending therebetween, each of said wheel hood coverings having an inner wall closing the inner end thereof to the interior of the body, doors for closing the bottom opening and having supporting means therefor between the opposite wheel hood coverings, said doors having lateral edge portions in relatively close proximity to the side sill structures with cracks therebetween and between the doors and the inner walls of the wheel hood cov-

erings, the combination of a tie plate extending transversely between the opposite wheel hood coverings and fixed at its opposite ends to the inner walls thereof, said tie plate having lateral wing sections on opposite edges thereof overlapping the cracks between the doors and the inner walls of the wheel hood coverings substantially throughout the width of the latter.

3. In a vehicle having a lading body with side sill structures separated and having a bottom opening therebetween for the discharge of lading therethrough, wheels and axles for supporting the lading body, wheel hood coverings connected with the lading body on opposite sides thereof over the wheels and with the axles extending therebetween, each of said wheel hood coverings having an inner wall closing the inner end thereof to the interior of the body, doors for closing the bottom opening and having supporting means therefor between the opposite wheel hood coverings, said doors having lateral edge portions in relatively close proximity to the side sill structures with cracks therebetween and between the doors and the inner walls of the wheel hood coverings, the combination of a tie plate extending transversely between the opposite wheel hood coverings and fixed at its opposite ends to the inner walls thereof, said tie plate having lateral wing sections on opposite edges thereof overlapping the cracks between the doors and the inner walls of the wheel hood coverings substantially throughout the width of the latter, said tie plate being formed of substantially V-shape and extending over the axles and the door supporting means.

4. In a vehicle having a lading body with side sill structures separated and having a bottom opening therebetween for the discharge of lading therethrough, wheels for supporting the lading body, axles for the wheels connected with the side sill structures, wheel hood coverings in the lading body on opposite sides thereof over the wheels and having inner walls closing the wheel hood coverings from the interior of the lading body, doors for closing the bottom opening between the side sill structures and between the wheel hood coverings with opposite edges in relatively close proximity to said side sill structures and said inner walls of the wheel hood coverings and with cracks therebetween, a tie plate substantially of inverted V-shape extending between opposite wheel hood coverings over the axle and door supporting means and having opposite ends thereof permanently fixed to the inner faces of the inner walls of the wheel hood coverings, said tie plate having lateral wing sections thereon at least at opposite ends thereof overlapping the cracks between the doors and the wheel hood cov-

erings throughout the width of each wheel hood covering.

5. In a vehicle having a lading body with side sill structures separated and having a bottom opening therebetween for the discharge of lading therethrough, wheels for supporting the lading body, axles for the wheels connected with the side sill structures, deeply recessed wheel hood coverings in the lading body on opposite sides thereof over the wheels and having inner walls closing the wheel hood coverings from the interior of the lading body, doors for closing the bottom opening between the side sill structures and between the wheel hood coverings with opposite edges in relatively close proximity to said side sill structures and said inner walls of the wheel hood coverings and with cracks therebetween, a tie plate substantially of inverted V-shape extending between opposite wheel hood coverings over the axle and door supporting means and having opposite ends thereof permanently fixed directly to the inner faces of the inner walls of the wheel hood coverings, said tie plate having lateral wing sections thereon at least at opposite ends thereof overlapping the cracks between the doors and the wheel hood coverings throughout the width of each wheel hood covering.

6. In a vehicle having a lading body with side sill structures separated and having a body opening therebetween for the discharge of lading therethrough, wheels for supporting the lading body, deeply recessed wheel hood coverings connected with the lading body on opposite sides thereof over the wheels, drop bottom doors having adjacent ends with a crack therebetween and extending transversely between the side sill structures in positions substantially to close said body opening, and a tie connection between the wheel hood coverings substantially over the crack between the doors, said tie connection having lateral edge portions extending over the cracks between the side edges of the doors and the adjacent side sill structures and substantially throughout the space between the wheel hood coverings and sealing said space at the lateral edges of the doors.
